METHOD AND APPARATUS FOR SEASONING ELECTRIC LAMPS OR SIMILAR LAMPS

Stanley R. Eade, Rugby, and William H. Dawson, Coventry, England, assignors to General Electric Company, a corporation of New York

Application April 4, 1942, Serial No. 437,724
In Great Britain May 6, 1941

5 Claims. (CL 176—8)

Our invention relates in general to the manufacture of electric lamps and similar devices, and more particularly to method and apparatus for aging or seasoning such electric devices.

In the manufacture of electric incandescent lamps, the completed lamp is usually subjected to an "aging" process wherein it is burned for a period at a varying voltage which is caused to follow a definite "program" or schedule relative to the lamp's rated voltage. Such aging is necessary to insure that the lamp will not arc out when it is first placed across the full line voltage; and in the case of coiled-coil filaments, to also help secure the desired grain structure in the filament. A preliminary separate or combined process may require that the lamp be burned on a supply whose voltage falls with, and is carefully related to, load current.

Mass production necessitates the use of a rotating machine to which lamps are fed and from which they are delivered after completing the burning period outlined above. The usual form of machine is arranged to connect a multiplicity of separate lamp sockets to appropriate voltage points during rotation of the machine by means of brushes co-operating with sectionalized slip rings. A disadvantage of this type of arrangement lies in the need for careful maintenance of the multiplicity of brush contact points involved, and a further disadvantage is apparent from the necessarily discontinuous nature of the voltage schedule or program. Our invention has for its object the elimination of these two disadvantages and the production of an equipment of more simple and rugged design.

The essential requirement in our method is that all or part of the electrical energy supplied to the lamps carried on the rotating member or turret of the machine shall be transferred to the lamps from the stationary portion of the machine by electromagnetic means. Furthermore, our apparatus is so arranged that the voltage applied to each lamp, as the lamp moves through its circular journey during one revolution or part revolution of the turret, follows the required schedule by suitably determining the angular distribution of the flux wave co-operating with the magnetic circuit or circuits attached to the rotary member.

The present invention consists in transferring electrical energy to a lamp or group of lamps, while they are being rotated, so that each lamp or group of lamps receives current from an independent source and the variation of applied voltage is dependent on the instantaneous position of the lamp or group.

It will be appreciated that the basic principle of our invention may be carried into effect in a number of different ways, and we will therefore describe one preferred arrangement which employs a mechanical design similar to the usual form of small induction voltage regulator.

In the accompanying drawing which illustrates this arrangement, Fig. 1 is a chart showing a typical form of voltage schedule to be applied wherein provision is made for loading and unloading the machine during a zero voltage period; Figs. 2 and 3 diagrammatically show the circuit arrangement and construction of our preferred method and apparatus in which an induction voltage regulator provides a voltage which is used to buck and boost the applied line voltage, thus giving the desired voltage cycle on any lamp or group of lamps during rotation through approximately one complete revolution of the rotor.

Referring to Fig. 2, each individual lamp 1 or group of lamps is connected in series with one of the rotating coils or secondaries 2 wound in the magnetic circuit of the rotating portion of the machine, and the so-connected lamp and secondary coil connected to a source of current supply by the aid of a pair of brushes and slip rings 3. For simplicity, we show only four lamp circuits, but it will be appreciated that this number may be greatly exceeded and will in fact be determined by the required "aging" period and the required output of the machine. It will be understood that Fig. 2 is purely diagrammatic and does not represent the actual construction of the machine. The flux co-operating with the rotating windings or secondaries 2 of the induction regulator is provided by a stationary primary winding 4, and the required angular distribution of magnetomotive force (MMF) is attained by a suitable choice of the pole arc to pole pitch ratio on the stationary member, and also if necessary by suitable grading of the air gap between the stationary and rotating parts of the induction regulator.

The general mechanical arrangement of our preferred construction is shown diagrammatically in Fig. 3, from which it will be seen that we make use of the induction regulator to form the basis of our design. The stationary member or primary of the induction regulator is shown at 5 and this is rigidly secured to the machine stand. The coil 4 of the primary 5 is connected by conductors 11, 12 across a source of current supply. The rotary member 6 is carried on bearings which rotate on the column 7 of the fixed member, and the necessary slow rotation of the

rotor 6 is provided by a worm drive 8 co-operating with a worm wheel 9 fixed to the base of the rotor. The rotor 6 is provided with spiders or lamp support arms 10 having sockets 13 for carrying the lamps 1 to be processed, the said support arms 10 being clamped or otherwise secured to suitable ears or lateral extensions 14 projecting out from the rotor body 6. The rotor coils or secondaries 2 of the induction regulator are mounted on the rotating member or turret 6 of the machine so as to rotate around and inductively couple with the primary or stationary member 5 of the induction regulator. One end 15 of each rotor coil 2 is carried out and connected to its lamp or group of lamps and the other side of the circuit is completed as previously described by the aid of conductors 16, 17 and a pair of slip rings and brushes indicated at 3.

As the rotary member 6 rotates, the secondary coils 2 and the stationary primary coil 4 of the magnetic circuit inductively co-operate with one another to supply a voltage to the lamps which will either buck or boost the applied mains voltage in varying degrees and at different time intervals, depending upon the instantaneous position of each individual secondary coil 2 with respect to the stationary primary coil 4. In this manner, the voltage actually applied to each lamp or group of lamps, as they move through their circular path during the rotation of the rotor or turret, can be made to follow the required schedule. Thus, the voltage supplied to each lamp may be made to follow the schedule shown in Fig. 1 wherein the "loading period" is that period, during the rotation of the turret 6 and the associated secondary coils 2, when the induced voltage supplied to each lamp fully bucks or counteracts the applied line voltage so as to result in a net zero voltage across each lamp. The "run-up period" indicated in Fig. 1 is that period, during the continued slow rotation of the turret 6 and associated secondary coils 2 about the primary coil 4, when the induced voltage supplied to each lamp gradually changes first from a maximum "bucking" value to zero value, and thence to a maximum "boosting" value so as to add to the applied line voltage and thus supply a maximum voltage to each lamp. The "maximum voltage period" in Fig. 1 is that period, during the further rotation of the turret 6, when the induced voltage supplied to each lamp remains at a maximum "boosting" value so as to supply, along with the applied line voltage, a maximum aggregative voltage to each lamp for effecting the aging of the lamp. This maximum voltage period is then followed by a final "run-down" period during which the induced voltage supplied to each lamp gradually changes from a fully "boosting" character back to a fully "bucking" or counteracting character wherein it fully bucks the applied line voltage so that the net voltage supplied each lamp returns to a zero value before the start of the next loading period immediately following.

It will be appreciated that the method outlined is only one of various possible ways in which our proposal may be carried into effect. The whole of the energy supplied to each lamp might, for instance, be supplied by the secondary 2 by transfer of the energy thereto from the primary coil and the schedule of voltage changes modified in

any desired manner. Furthermore, the functions of the primary and secondary coils might be reversed.

What we claim as new and desire to secure by Letters Patent of the United States is:

1. The method of seasoning an electric lamp which comprises connecting the lamp in series with one of the inductively co-operating coils of an induction voltage regulator, connecting the said series-connected lamp and coil to the poles of a source of current supply, connecting the other of said inductively co-operating coils to the poles of the said source of current supply, and rotating the rotor of said induction voltage regulator to thereby produce an induced voltage in the said series-connected lamp and coil circuit which will alternately buck and boost the line voltage applied to the said series-connected lamp and coil circuit.
2. The method of seasoning an electric lamp which comprises connecting the lamp in series with the secondary coil of an induction voltage regulator, connecting the said series-connected lamp and secondary coil to the poles of a source of current supply, connecting the primary of said induction voltage regulator to the poles of the said source of current supply, and rotating the rotor of said induction voltage regulator to thereby produce an induced voltage in the said series-connected lamp and secondary coil circuit which will alternately buck and boost the line voltage applied to the said series-connected lamp and secondary coil circuit.
3. Apparatus for seasoning an electric lamp comprising an induction voltage regulator having a stator and a rotor provided with coils arranged to inductively couple with each other upon rotation of said rotor, a socket on said rotor for supporting the electric lamp thereon, means to rotate said rotor, conductors connecting the said rotor coil in series with a lamp in said socket and across a source of current supply, and other conductors connecting the stator coil across the said source of current supply.
4. Apparatus for seasoning an electric lamp comprising an induction voltage regulator having a stator provided with a primary coil and a rotor provided with a secondary coil, a socket on said rotor for supporting the electric lamp thereon, means to rotate said rotor, conductors connecting the said secondary coil in series with a lamp in said socket and across a source of current supply, and other conductors connecting the said primary coil across the said source of current supply.
5. Apparatus for seasoning electric lamps comprising an induction voltage regulator having a stator provided with a primary coil and a rotor provided with a plurality of secondary coils, said primary coil and said secondary coils being arranged to inductively couple with one another upon rotation of said rotor, a plurality of sockets on said rotor for supporting a plurality of electric lamps thereon, means to rotate said rotor, conductors connecting separate ones of said secondary coil in series with a lamp in separate ones of said sockets and across a source of current supply, and other conductors connecting the said primary coil across the said source of current supply.
